UNITED STATES PATENT OFFICE.

ISIDOR M. JACOBS, OF KANSAS CITY, AND WILLIAM CRAMER, OF ST. LOUIS, MISSOURI,
ASSIGNORS TO TRUCK, TRACTOR, AND MANUFACTURING COMPANY, OF ST. LOUIS,
MISSOURI, A CORPORATION OF MISSOURI.

RADIATOR-CAP.

1,314,521.

Specification of Letters Patent. **Patented Sept. 2, 1919.**

Application filed April 17, 1918. Serial No. 229,164.

To all whom it may concern:

Be it known that we, ISIDOR M. JACOBS and WILLIAM CRAMER, citizens of the United States, residing, respectively, at the city of 5 Kansas City, county of Jackson, and State of Missouri, and at the city of St. Louis, in the State of Missouri, have invented certain new and useful Improvements in Radiator-Caps, of which the following is a specification.

This invention is an improvement relating to the subject-matter described in the applications of these same inventors for patents for radiators, Serial Nos. 197,542, and 15 198,649, filed, respectively, in the United States Patent Office on October 20 and October 26, 1917.

In the accompanying drawings forming part of this specification, in which like numbers of reference denote like parts wherever they occur,

Figure 1 is a front elevation;

Fig. 2 is a front elevation with parts broken away, and with parts in a different 25 position from that illustrated in Fig. 1;

Fig. 3 is a partial sectional view, one of the movable members being shown in dotted lines in successive positions; and

Fig. 4 is a side elevation.

The object of this invention is to provide ready access to the radiator neck of the inside radiator of the construction illustrated and described in either of the above-mentioned applications for patent, or any similar construction. If the water in the radiator has become hot or steaming, it may be objectionable to reach the hand in to unscrew the inside radiator cap 1 or a like member from its place on the neck 2, and to introduce fresh water into the radiator it is necessary to remove whatever kind of cap there may be on neck 2 or equivalent part. The present construction, by allowing the folding back of straps 3, allows ready, free, 45 and convenient access to neck 2 of cap 1.

Wings 4 on straps 3 encircle neck 2, and taper upwardly, so as to retain inwardly tapered cap 5 by frictional contact.

Cap 5 binds wings 4 together over cap 1 50 and neck 2 (as best seen in Fig. 1), and this holds straps 3 in the position shown in Fig. 1 and in full lines in Fig. 3.

The straps 3 are pivoted at 6 to the dummy radiator 7, which contains the inside or salvaged radiator 8. The relation of the 55 radiators 7 and 8 to the hood 9 is that which is ordinary and common.

Cap 5 is finished at one end with the tit 10, having through it a hole 11. When cap 5 has been removed from wings 4, it can be 60 inverted as shown in Fig. 2, with the tit 10 inserted in the mouth of neck 2, which enables the use of cap 5 like a funnel.

Having thus described this invention, we hereby reserve the benefit of all changes in 65 form, arrangement, order, or use of parts, as it is evident that many minor changes may be made therein without departing from the spirit of this invention or the scope of the following claims.

We claim:

1. The combination of a true and false radiator, the one inclosed by the other, and the false radiator having an opening near its top, strap means pivoted to the said false 75 radiator and adapted to close the said opening, a neck for the said true radiator projecting through the said opening, and a cap adapted to bind the said strap means in closed position and to inclose the said neck, 80 the said strap means having wings thereon and the said wings being inclosed within the said cap, the said wings being exteriorly tapered and the said cap being interiorly 85 tapered.

2. In combination, a false radiator provided with an opening, a true radiator provided with a neck which extends through the opening, straps hinged to the top portion of the false radiator and provided at 90 their free ends with wings adapted to embrace the neck when the opening is closed, and a cap which embraces and holds the wings closed and which incloses the top 95 of the neck, said cap having a reduced extension provided with an opening and which may be inverted when the straps are open and the reduced end fitted in the top of the neck to feed water to the true radiator.

In testimony whereof we hereunto affix our signatures.

ISIDOR M. JACOBS.
WILLIAM CRAMER.
